UNITED STATES PATENT OFFICE.

FRANCIS H. PATTEN, OF WILKINSBURG, PENNSYLVANIA, ASSIGNOR TO WESTINGHOUSE ELECTRIC AND MANUFACTURING COMPANY, A CORPORATION OF PENNSYLVANIA.

CUT-OUT.

1,311,460.

Specification of Letters Patent. Patented July 29, 1919.

Application filed September 10, 1914. Serial No. 861,042.

To all whom it may concern:

Be it known that I, FRANCIS H. PATTEN, a citizen of the United States, and a resident of Wilkinsburg, in the county of Allegheny and State of Pennsylvania, have invented a new and useful Improvement in Cut-Outs, of which the following is a specification.

My invention relates to cut outs, and it has particular reference to such mechanisms as are employed in connection with the electrical systems of automobiles or other motor vehicles.

My invention has for its object to provide a cut out which has a simple and convenient means for adjusting the voltage value at which it operates to control an electrical circuit.

I provide a cut out having an armature member, the normal position of which is adjustable relatively to the electromagnet which actuates it to control an electrical circuit. The armature member is arranged for lateral and longitudinal movements, suitable guiding means being provided for the armature member during such movements.

The details of my invention will be described in connection with the accompanying drawings in which Figure 1 is a side view, partially in section and partially in elevation, of a cut out constructed in accordance with my invention. Figs. 2 and 3 are plan views of details. Fig. 4 is a diagrammatic view of circuits and apparatus employed in connection with my invention. Fig. 5 is a view, in section, of the stationary contact member and associated parts.

Referring particularly to Figs. 1, 2 and 3, the cut out 1 comprises a base member 2 of magnetic material upon which are mounted core members 3 and 4 that are respectively surrounded by a coil 5 of comparatively fine wire and a coil 6 of relatively coarse wire. The coils 5 and 6 are adapted to be connected in shunt and series relations, respectively, to a source of current. A bar 7 of non-magnetic material is fixed to the core members 3 and 4 by screws 8 which constitute pole pieces for the core members. The bar 7 is provided, at one end, with a raised portion 9 to which is secured one end of a blade spring 10.

A movable armature member 11 is attached to the opposite end of the spring 10. The armature member 11 is provided, at one end, with a reduced portion 12 which pro-

jects through a suitable slot 13 in the bar 7. This construction permits a slideable movement of the armature member 11 relatively to the bar 7 when the armature member is actuated laterally. The opposite end of the armature 11 is provided with a slot 14 to receive an adjustable screw 15 that is connected to the bar 7. The head of the screw 15 limits the outward movement of the armature member 11 and thus determines the normal position of the armature member relatively to the pole pieces 8. A contact member 16, which is mounted upon, and connected to, the armature member 11, coacts with a stationary contact member 17 that is mounted upon and connected to a horizontally projecting portion of an insulated terminal member 18 that consists, either wholly or in part, of phosphor bronze or other suitable resilient material. The contact member 17 is connected to one terminal of each of the coils 5 and 6.

Referring now to Fig. 4, the coils 5 and 6 are respectively in shunt and in series with the armature of a dynamo-electric machine 19, the coil 5 being in series with the shunt field winding 20. These connections are preferably made within the structure of the dynamo-electric machine and form a part of its interior circuits. A storage battery 21 is connected directly to one terminal of the dynamo-electric machine, the other terminal of the battery being grounded, as shown. The contact member 16 is grounded through the spring 10, the bar 7, the core members 3 and 4 and the frame of the dynamo-electric machine.

It may be assumed that the generator 19 is operatively connected to the engine of an automobile (not shown). When the engine starts under its own power, current flows from one terminal of the generator through the series field winding 22, series coil 6, shunt coil 5, and shunt field winding 20 to the other terminal of the generator. As the generator speed increases, a predetermined voltage is reached at which the coils 5 and 6 are sufficiently energized to draw the armature member 11 downwardly against the tension of the spring 10 to effect the engagement of the contact members 16 and 17. The battery-charging circuit, which is thereby completed, extends from one terminal of the generator, through the series field winding 22, series coil 6, contact members 17 and 16, and

spring 10, to ground, and thence, through the battery 21, to the other terminal of the generator. The battery 21 will be charged as long as the voltage of the generator exceeds that of the battery.

In case the generator voltage falls below that of the battery, the direction of flow of current in the charging circuit will be reversed. The series coil 6, which normally 10 assists the shunt coil 5, now opposes the latter, and, as a result, the spring 10 draws the armature member 11 upwardly. The charging circuit is thus broken by the separation of the contact members 16 and 17, 15 and it cannot be closed again until the generator voltage has reached the predetermined value at which the cut out is adjusted to operate.

The cut out will be adjusted to operate 20 at a predetermined voltage when it is assembled at the place of manufacture. This predetermined value may, however, be varied at any time while the cut out is in operation by adjusting the screw 15 and 25 thereby varying the normal position of the armature member 11 relatively to the pole pieces 8.

It will be noted that I provide a switching device having a simple and convenient 30 means for adjusting the voltage value at which it operates to control a battery-charging circuit. The construction whereby the armature member is connected to the supporting bar by the spring 10 and the stationary contact member is resiliently mounted provides a sliding or wiping engagement 35 of the contact members. This action is produced by reason of the fact that the end of the armature member to which the spring 40 and contact member are attached moves in a circular path about the fixed end of the spring while the other contact member moves in a straight line when the electromagnet actuates the armature member 45 downwardly. The resilient mounting of the stationary contact member also insures that the contact members will not be damaged by the impact of their engagement or by excessive vibration of the mechanism. 50 The slidable mounting of the armature member avoids the use of pivotal connections and insures that the movement of the armature member is always free and unobstructed. 55 It is understood that such modifications may be made without departing from the spirit of my invention as fall within the scope of the appended claims.

I claim as my invention:

60 1. In a cut out, the combination with a pair of relatively movable coöperating contact members, of a laterally and longitudinally movable armature member for carrying one of said contact members, and means, 65 comprising an electromagnet, for operating

said armature member laterally and longitudinally and causing said contact members to have a substantial wiping or sliding engagement with one another.

2. In a cut out, the combination with a 70 pair of relatively movable coöperating contact members, of a laterally and longitudinally movable armature member for carrying one of said contact members, means, comprising an electromagnet, for operating said 75 armature member and causing said contact members to have a wiping or sliding engagement with one another that is sufficient to prevent pitting of said contacts, and means for guiding the movements of said armature 80 member.

3. In a cut out, the combination with a pair of relatively movable coöperating contact members, of a laterally and longitudinally operable armature member for carrying one of said contact members and means, comprising an electromagnet, for operating said armature member to move said contact members in parallel planes and in intersecting directions while effecting engagement. 90

4. In a cut out, the combination with an electromagnet and a pair of relatively movable contact members, of a supporting member, an armature member for carrying one of said contact members and arranged for 95 slideable movement relatively to said supporting member, and a spring connecting said armature member to said supporting member for producing longitudinal movement of said armature member when the latter is actuated 100 laterally.

5. In a cut out, the combination with an electromagnet, a supporting member having a slot, and a spring secured to said member, of a longitudinally movable armature member 105 attached to said spring and having a portion projecting into said slot, a stationary contact member, a movable contact member carried by said armature member, and means for adjusting the normal position of said 110 armature member.

6. In a cut out, the combination with an electromagnet, of an armature operable thereby, a contact member carried by said armature, a resiliently mounted contact member engageable by the aforesaid contact member, and means for yieldingly supporting and actuating said armature so that it will have a predetermined movement of translation to cause said contact members to 115 slide relatively and in contact with one another when the armature is attracted by said electromagnet.

7. In a cut out, the combination with a stationary contact member resiliently mounted, of a movable contact member for coacting therewith, an armature member for carrying said movable contact member, and means for producing simultaneous lateral and longitudinal movements of said armature, said 120 125 130

means comprising a spring for yieldingly retaining said armature member in an inoperative position.

8. In a cut out, the combination with a stationary contact member resiliently mounted, of a movable contact member for coacting therewith, an armature member for carrying said movable contact member, and means for producing simultaneous lateral and longitudinal movements of said armature to cause a sliding engagement of said contact members.

9. In a cut out, the combination with a stationary contact member resiliently mounted, of a movable contact member for coacting therewith, an armature member for carrying said movable contact member, and means for producing simultaneous lateral and longitudinal movements of said armature to cause a sliding engagement of said

20 contact members, said means comprising a spring attached to said armature member at the end adjacent said contact member, the other end of said armature being loosely mounted.

25 10. In a cut out, the combination with an electromagnet of an armature operable thereby, a contact member carried by said armature, means for supporting said armature in operative position comprising a bar, means

30 for determining the longitudinal and lateral movements of said armature, a leaf spring secured to said armature and to said bar, and a resiliently mounted contact member adapted to be slidably engaged by said contact

35 member on the armature.

11. In a cut out, the combination with a pair of coöperating contact members, of re-

silient means for supporting each of said contact members, means for moving said contact members into and out of engagement with each other and means for causing said contact members to move in parallel planes and in intersecting directions while effecting engagement.

12. In a cut out, the combination with a pair of relatively movable coöperating contact members, of a laterally and longitudinally movable armature member for carrying one of said contact members, means comprising an electromagnet, for operating said armature member and causing both of said contact members to have a sliding movement in different directions relative to each other to prevent the pitting of said contact members, and means for guiding the movements of said armature member.

13. In a cut out, the combination with a resiliently mounted contact member, of a movable contact member for co-acting therewith, an armature member serving to carry said movable contact member and mounted for simultaneous lateral and longitudinal movements and means, comprising said armature member, for moving both of said contact members in different directions relative to each other while effecting engagement.

In testimony whereof, I have hereunto subscribed my name this 28th day of Aug., 1914.

FRANCIS H. PATTEN.
